RESETTING FUSE PLUG

Louis C. Ondrejca and Joseph F. Ondrejca, Orefield, Pa., assignors of one-third to Francis Ondrejca, Orefield, Pa.

Application June 13, 1947, Serial No. 754,412

3 Claims. (Cl. 200—106)

1

The present invention relates to new and useful improvements in fuses, or circuit breakers and more particularly to a resetting fuse for reestablishing a circuit following an interruption thereof due to an overload.

An important object of the invention is to provide a screw type fuse plug including a housing for an automatic circuit breaker having push button operated mechanism for reestablishing the circuit.

A further object is to provide safety means locking the contacts of the circuit breaker in open position to prevent premature or accidental resetting of the device.

Another object is to provide a device of this character of simple, practical and compact construction, that is efficient and reliable in use, relatively inexpensive to manufacture and otherwise well adapted for the purpose for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the automatic fuse plug;

Figure 2 is an enlarged longitudinal sectional view showing the resetting push button depressed;

Figure 3 is a similar view showing the push button in projected position;

Figure 4 is a plan view of the outer end of the fuse plug with the cap removed;

Figure 5 is a longitudinal sectional view taken on a line 5—5 of Figure 3, and;

Figure 6 is a side elevational view of the porcelain body removed from the housing and showing the swingable contact of the circuit breaker.

Referring now to the drawings in detail, wherein for the purpose of illustration we have disclosed a preferred embodiment of our invention, the numeral 5 designates a cylindrical housing of insulation material having a reduced inner end 6 provided with a metal threaded collar 7 forming a plug for threading in a conventional electric socket. A conductor 8 extends longitudinally through the reduced end 6 and into a tubular contact 9 projecting from the end of the plug to provide the base contact for the plug.

A porcelain body 10 is removably carried in the housing 5 in which the upper portion of the conductor 8 is embedded and exposed at its upper end against a porcelain shoulder 12 to provide a

2

stationary contact 13. Also embedded in the body 10 is a conductor 14 having one end exposed against the shoulder 12 in spaced relation from the contact 13 to provide a second contact 15. The contacts 13 and 15 are bridged by a movable contact 16 carried at the free end of a spring arm 17 which has its other end secured to one end of a shaft 18 journaled in a porcelain shoulder 18a of the body.

10 The conductor 14 extends transversely of the body 10 and is connected at its other end to a conventional relay 19 recessed in an adjacent side of the body and to which is also connected the conductor collar 7 of the plug by means of a conductor rod 20 which extends through an opening 21 adjacent the lower end of the housing to engage the collar.

15 The relay includes a pivoted circuit breaking armature 22 held in open position by a wire spring 23 at its pivot and the pivoted end of the armature 22 is formed with a lateral and inwardly extending finger 24 which underlies one end 25 of a trip lever 26.

20 The lever 26 is secured adjacent its center on a pin or shaft 27 journaled in a porcelain support 28 formed integrally with the body and the shaft 27 is also formed with a flat locking or trip notch 29 movable into and out of the path of a dog 30a formed on a toggle link 30 pivoted to the body and operated by a push button 31. A coil spring 32 carried by the shaft 27 holds the end 25 of the lever 26 downwardly and with the locking notch 29 raised for locking engagement with the toggle link 30.

25 An adjustable stop 33 engaging the other end 34 of lever 26 limits the downward movement of end 25.

30 The push button 31 projects outwardly through an opening 35 in a cap 36 secured to the top of the housing 5 and a trip lever releasing push button 37 is slidably mounted in the cap with a coil spring 37a raising the push button 37 in its projected position. The end 34 of the trip lever 26 is formed with a lateral shoulder 38 in the path of downward movement of the push button 37 to actuate the lever in a manner to release the locking notch 29 from the toggle link 30.

35 The toggle link 30 includes a link 39 having an extension 40 pivoted thereto and also secured to the shaft 18. A coil spring 41 mounted on the shaft 18 and engaging the extension 40 exerts its influence in a manner to rotate the shaft 18 in a direction to swing the arm 17 away from the contacts 13 and 15 against a stop 42 to hold the circuit open.

A coil spring 43 positioned in a recess 44 in the body under the toggle link 30 holds the push button 31 in a raised position. In the operation of the device the contact 16 is moved into its closed position with contacts 13 and 15, as shown in Figure 6, by depressing button 31 which rotates the shaft 18 through the toggle link members 39 and extension 40. The dog 30a on the toggle link 30 bears against the trip notch 29 to hold the toggle firmly during this depressing action of the button 31 against the opposing force of the spring 41 for link members 39 and spring 17 for contact 16. The contact 16 is held in its closed position by movement of toggle links 39 downwardly past center, as shown in Figure 2, and which thus holds push button 31 in its depressed position.

With contact 16 closed current passes through relay 19 without attracting the armature 22 which is held away from the surface of the relay by the spring 23.

Should an overload occur in the circuit, the armature 22 will be attracted to the relay to swing the lower end of the armature inwardly, such movement of the armature 22 raising the finger 24 of the armature to engage the end 25 of the trip lever 26 to rock the shaft 27 against tension of spring 32 and release the notch 29 from the dog 30a, whereupon the spring 43 will raise toggle 30 and push button 31 and spring 17 will swing contact 16 open to break the circuit.

The circuit is restored by again depressing the button 31.

Safety push button 37 is used to manually break the circuit, when desired, the depressing of the button 37 engaging the lateral shoulder 38 on the end 34 of the lever 26 to rock the lever and shaft 27 to release dog 30a which holds the toggle 30 and push button 31 in its set position.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A resetting fuse plug comprising a hollow body having a pair of contacts at its inner end to provide a circuit connection with an electrical socket, an insulated body removably positioned in the hollow body, and an automatic circuit breaker carried by the body and comprising a pair of stationary contacts and a movable contact movable into and out of engagement therewith, spring means biasing the movable contact to an open position, a trip device holding the movable contact in closed position and including a rockable shaft having a locking notch, a push button operated resetting toggle member having a dog engageable with the notch for locking the shaft against movement, means connecting the toggle member to the movable con-

tact, and electrical means including an electromagnet having an armature with an offset portion engageable with said rockable shaft, said electromagnet included in the circuit and responsive to an overload therein to operate said rockable shaft to release said toggle member thereby effecting opening of said movable contact.

2. The combination of claim 1 wherein said insulated body includes a wall portion, said contacts being located on one side of said wall portion and said toggle member, shaft and armature being located on the other side of said wall portion, said means connecting said toggle member to said movable contact comprising a pin extending through said wall portion.

3. A resetting fuse plug comprising a hollow body having a pair of contacts at its inner end to provide a circuit connection with an electrical socket, an insulated body removably positioned in the hollow body, and an automatic circuit breaker carried by the body and comprising a pair of stationary contacts and a movable contact movable into and out of engagement therewith, spring means biasing the movable contact to an open position, a trip device holding the movable contact in closed position and including a rockable shaft having a locking notch, a push button operated resetting toggle member having a dog engageable with the notch for locking the shaft against movement, a pin rotatable on the body and terminally fixed to the movable contact and the toggle member whereby engagement of the dog with the notch will retain the movable contact in engagement with the stationary contacts, and means for releasing the trip device and including a lever crosswise of one end of the shaft, an armature pivotally mounted on the body and having an offset extending portion engageable with the lever to rock the shaft in a trip releasing movement, electromagnet means in the circuit and supported on the body for actuating the armature to its shaft rocking position, and a push button operating means engaging the offset portion to independently actuate the shaft in its trip releasing movement.
